Primary Examiner — Rosemary K Tarcza*Assistant Examiner* — Seth David Kumpf(74) *Attorney, Agent, or Firm* — POSZ LAW GROUP, PLC(57) **CLAIM**

The ornamental design for accumulator charging apparatus, as shown and described.

DESCRIPTION

1. Accumulator charging apparatus

1.1 is a rear elevational view of an accumulator charging apparatus, showing our new design;

1.2 is a perspective view thereof;

1.3 is a side elevational view thereof; and

1.4 is a top plan view thereof.
